DOOR FASTENER

William M. Dwyer, Chicago, Ill., assignor to W. H. Miner, Inc., Chicago, Ill., a corporation of Delaware

Application February 14, 1940, Serial No. 318,905

10 Claims. (Cl. 70—145)

This invention relates to door fasteners for refrigerator automobile trucks having hinged doors, and more particularly to fasteners which are operative to hold the doors closed when the same are slammed shut.

One object of the invention is to provide a door fastener for hinged doors of refrigerator trucks, comprising manually operated means for positively camming the door either open or closed, wherein said means is also effective to automatically fasten the door when the same is slammed shut.

Another object of the invention is to provide a door fastener for hinged doors of truck bodies which is effective to securely fasten the door in closed position when the same is slammed shut, and which may be released from the interior of the body of the truck, so that the door may be opened by the attendant in the event of his being confined in the truck by accidental slamming shut of the door.

A further and more specific object of the invention is to provide a door fastener for hinged doors comprising a lever actuated, rotary operating member having eccentric cam means adapted to engage with slotted keeper means for forcing the door tightly closed and prying the same open, wherein the keeper means is yieldingly movable and operates as a spring latch to permit engagement therewith of the cam means to automatically latch the door when the same is forcibly slammed shut.

A still further object of the invention is to provide a door fastener of simple and rugged design, comprising a lever operated rotary member having eccentric keeper engaging cam means thereon adapted to cooperate with the slot keeper.

Other objects of the invention will more clearly appear from the description and claims hereinafter following.

In the drawings forming a part of this specification, Figure 1 is a broken side elevational view of a portion of the wall of the body of a refrigerator automobile truck, the wall being provided with an opening which is closed by a single door, said view illustrating my improved fastener in connection therewith. Figure 2 is a view similar to Figure 1, on an enlarged scale, of a fragment of the door and side wall of the truck body, illustrating the improved fastener more in detail. Figure 3 is a vertical sectional view, corresponding substantially to the line 3—3 of Figure 2, showing the improved fastener in elevation, the inner side of the wall of the truck

body being broken away. Figure 4 is a vertical sectional view, corresponding substantially to the line 4—4 of Figure 2, the door being shown broken to more readily accommodate the figure to the sheet of the drawing. Figure 5 is an elevational view, looking from right to left in Figure 4. Figure 6 is a vertical sectional view, corresponding substantially to the line 6—6 of Figure 2. Figure 7 is a horizontal sectional view, corresponding substantially to the line 7—7 of Figure 2. Figure 8 is a vertical sectional view, corresponding substantially to the line 8—8 of Figure 3, illustrating a portion of the fastener shown in said figure. Figure 9 is a view, similar to Figure 6, but showing the parts in different position.

In said drawings, 10 indicates the side wall of a chamber, such as the body of a refrigerator automobile truck. The wall 10 has the usual door opening 11 closed by a single door 12. The door 12 is of the swinging type and is supported by a pair of hinges 13—13 secured to the wall 10 at one side of the door opening.

My improved door fastener comprises broadly a keeper housing A; a rockable or pivoted keeper B; a spring C yieldingly opposing rocking of the keeper B; a key controlled lock D; a lever supporting housing E; an actuating lever F for rocking the keeper from the interior of the automobile refrigerator body; an actuating rod G connected to the lever for swinging the keeper B; a supporting bracket H on the outer side of the door; a keeper engaging crank member K journaled in said bracket; and an actuating handle lever L fixed to said crank member.

The housing A includes a base plate 14 by which the housing is secured to the wall 10 of the truck body. Upstanding from the base plate 14 are spaced, parallel, longitudinal walls 15 and 16 forming the side walls of the housing, and spaced, inclined, transverse walls 17—17 forming the top and bottom or end walls of said housing. The front of the housing is partly closed by inclined wall sections 18—18 at the top and bottom thereof. The wall sections 18—18 are continuous with the end walls 17—17. The front of the housing A is thus provided with a central opening 19 to permit entrance of the keeper engaging portion of the crank member K, as hereinafter pointed out. The side wall 16, which is the wall adjacent the door opening 11, is cut away, as most clearly shown in Figures 4 and 7, to provide an opening 20 to accommodate the keeper engaging portion of the crank member K for movement into and out of the housing. The back of the housing is open, as indi-

cated at 21, the base plate 14 being cut out for this purpose.

As shown most clearly in Figure 6, the lower front wall section 18 of the housing is thickened, and said thickened portion presents a substantially flat abutment face 22. On said face 22 there is provided an inwardly projecting centering boss 23 adapted to engage within the end of the spring C to center the latter. The side walls 15 and 16 of the housing A are provided with transversely aligned, outwardly projecting, inwardly opening pockets 24 and 25 adjacent to the base of said housing, providing seats for opposite ends of a pivot pin 26. The opening at the back of the housing A is enlarged at the lower end portion of said housing to provide clearance to admit entrance of the pin 26 and placing of the same in the seats 24 and 25.

The keeper B is in the form of a rocker comprising spaced, platelike sections 27 and 28 connected by transverse webs 29 and 30 defining an outwardly opening cam slot 31 therebetween. The inner ends of the walls 29 and 30 are connected by a rounded portion 32 which closes the slot at its inner end. The wall 29 is shorter than the wall 30, as clearly shown in Figures 6 and 9, and is thickened at the mouth of the slot, thus providing an inclined cam face 33 at an angle to the slot, for a purpose hereinafter pointed out. The keeper B is further provided with a tail portion 34 formed by continuations of the spaced platelike sections and the transverse wall 30. The tail portion 34 has a seat 35 opposite to the abutment face 22 of the housing, and this seat has a spring centering boss 36 projecting therefrom. On the inner side, that is, the side opposite to that provided with the boss, the tail portion 34 is recessed or socketed, as indicated at 37, to provide a seat for the outer end of the actuating rod G. The platelike section 28 closes the corresponding side of the slot 31 and the plate 27 is slotted in registration with the slot 31 to accommodate the keeper engaging portion of the crank member K for in and out movement. At the inner side of the keeper B, the edges of the platelike sections are recessed, as indicated, to provide pivot seats 38-39 adapted to engage over the pin 26 to support the keeper B for rocking movement. The keeper, which is pivotally supported on the pin 26 within the housing A, normally bears against the inner side of the top wall 18 of the housing, as clearly shown in Figure 6.

The spring C is of helical form and interposed between the abutment 22 of the wall 18 at the lower end portion of the housing A and the tail 34 of the rocker B. This spring is held in centered position by the bosses 23 and 36 of the housing A and rocker B respectively, the expansive action of the spring normally holding the rocker B in the position shown in Figures 1, 2, 3, 4, and 6 with the face of the enlarged portion of the wall 29 which carries the cam face 33 abutting the wall 18 of the housing, with the cam face exposed beyond the end edge of said wall. The platelike section 28 is perforated, as indicated at 39, to receive the locking projection of the key operated lock D, as hereinafter described. The perforation is located between the opposed side walls of the slot 31 of said keeper B.

The key controlled locking member D is mounted in a socket provided by a cylindrical, tubular projection on the wall 15 of the housing A. This key controlled locking member is of well-known

design, being in the form of a bolt having a projecting locking pin portion 41 adapted to engage through the perforation 39 of the keeper B to lock said keeper against rocking movement. As is well known in key operated locking means of this type, the lock is spring pressed, and when unlocked projects outwardly beyond the sleeve 40. To operate the same to lock the rocking keeper B, it is pressed inwardly to engage the pin 41 in the opening 39 of the keeper, the plunger and the pin being held in the locking position by the usual well-known means comprising a spring pressed detent engaging in a locking socket or recess in the projection on the wall 15 of the housing A. When unlocked by the usual key inserted in the member D, the spring action of the lock retracts the pin 41 while the lock is being projected to its outer position, thus unlocking the rocking keeper B.

20 The housing A may be secured to the wall 10 by any suitable means, and, as shown, is held thereto by screws extending through the base-like plate portion 14 of said housing into the wall 10.

25 The supporting bracket H comprises a plate-like base member 42 having spaced, outstanding journal bearing members 43 and 44 thereon, said bearing elements having aligned cylindrical bearing openings. The bearing opening of the element 44 is preferably closed at its outer end. This bracket is fixed to the door adjacent the free edge thereof in alignment with the keeper housing A by any suitable means, such as screws, extending through the base plate 42 and into the door member.

30 The keeper engaging crank member K comprises a short shaftlike section 45 having a radially extending crank arm 46 at the outer end thereof provided with a keeper engaging lug 47. The lug 47 is preferably of the cross sectional outline shown in Figure 6, the same being in the form of a cylindrical pin having one side flattened, as shown, to provide a straight face 48 thereon. The shaft 45 has a cylindrical portion 49 adjacent the crank arm 46 journaled in the opening of the bearing element 43, a cylindrical portion 50 at the other end, and an intermediate portion 51 of angular cross section. The portion 50 is of smaller diameter than the section 49 and rotatably fits the bearing opening of the bearing element 44, which opening is also of smaller diameter than the opening of the bearing element 43. The cylindrical portion 50 of the shaft is provided with an annular groove 52 between its ends. A pin 53 extending through suitable openings of the bearing element 44 and engaged in said groove 52 holds the shaft against accidental removal in endwise direction.

35 The operating handle lever L has an enlarged head portion 54 at its inner end provided with an opening 55 of angular cross section which snugly fits the angular portion 51 of the shaft 45. The handle lever L is thus securely fastened to the shaft 45 to rotate the latter as said handle lever is swung toward and away from the door.

40 The housing E comprises a platelike base portion 56, spaced side walls 57-58 and spaced end walls 59-60 outstanding from said base plate, and an inclined outer wall 59. The housing is open at the inner side, as indicated at 60, and also has an opening 61 in the outer wall 59 and the bottom end wall 58 thereof to accommodate the lever F for swinging movement. The housing E is secured to the inner side of the wall

10 of the truck body adjacent the opening 11 in horizontal alignment with the bottom end portion of the housing A which is at the outer side of said wall. Any suitable means, such as screws, extending through the base plate 56 of the housing E and into the wall 10, serve to secure said housing in position.

The operating lever F is pivoted between its ends on a pivot bolt 62 fixed in the side walls 57-57 of the housing E and extending through a pivot opening in said lever. The lever comprises a short arm 63 and a long arm 64 extending at an angle to each other in opposite directions from the pivot point of said lever. The long arm 64 extends through the opening 61 of the housing and forms the handle member of the lever. The short arm 63 is forked at its outer end, as indicated at 65, the arms of the fork being provided with aligned pin receiving openings.

The rod G is in the form of a cylindrical bar headed at one end, as indicated at 66, said headed end being perforated to provide an eye portion. The rod G is pivotally connected to the short arm 63 of the lever F at said headed end 66 by a pivot pin 67 extending through the openings of the forked portion 65 and the eye-shaped headed end 66 of said rod, which headed end is accommodated between the arms of the fork.

The rod G extends freely through a bore or opening 68 provided in the wall 10, as clearly illustrated in Figure 9, said opening serving as a guide for the rod and is so placed as to hold the rod properly aligned with the tail portion 34 of the keeper B and allow the seating of the end of the rod in the socket 37 of said keeper. The bore 68 is of ample size to provide the required clearance for angling of the rod as it is operated to swing the keeper B on its pivot.

The operation of my improved door fastener in opening the door, assuming the door to be in the locked position shown in Figures 1 to 8 inclusive, is as follows: The key controlled lock D is first unlocked in the usual manner, thus withdrawing the pin 41 from locking engagement with the keeper B. The withdrawal of the pin 41 also frees the keeper engaging cam lug 47 of the crank member K so that the latter may be rotated to pry the door open. In this connection it is pointed out that the pin 41 protrudes into the cam slot of the keeper B, as clearly indicated in Figures 6 and 8, in the path of swinging movement of the cam lug 47, thereby locking the crank member K against rotation.

After the cam lug 47 has been cleared for operation by withdrawal of the pin 41, the attendant swings the handle lever L away from the door and upwardly, thereby rotating the keeper engaging crank member K. The keeper engaging cam lug is thus swung against the inclined rear wall of the cam slot of the keeper B, thereby camming the door partly open. The door may then be manually swung fully open in the usual manner.

The door may be closed by either moving the same to partly closed position and then forcing it tightly closed by operation of the keeper engaging crank member, or by slamming the same shut, thereby automatically locking the door by the latching action of the keeper.

In closing the door by actuation of the crank member, the operation is as follows: The attendant first swings the door to partly closed position to bring the keeper engaging crank member K into cooperative relation with the keeper B.

While the door is being swung to this position, the operating handle lever L may be in the pendant position shown in Figures 1 to 5 inclusive. However, it is preferable that the same be raised to a position at right angles to the plane of the door so that the keeper engaging lug 47 of the crank member K is rotated to a position of alignment with respect to the entrance of the slot 31 of the keeper B so that it will enter this slot as the door is pushed to partly closed position. In the event that the lever has been left in pendant position while the door is being swung to partly closed position, the lever must then be raised to horizontal position to align the keeper engaging lug 47 of the crank member K with the slot of the keeper so that the cam lug may cooperate with the slot of the keeper. The actuating handle lever L is then swung downwardly and toward the door, thus rotating the crank member K in a reverse direction to that hereinbefore described, causing the cam lug 47 to enter the cam slot 31 of the keeper B and swing against the inclined outer wall of said slot to cam the door inwardly to tightly closed position. In thus camming the door shut, the flat portion 48 of the cam lug will be brought into flat face contact with the inner surface of the front wall of the slot 31 of the keeper, thereby locking the crank member against accidental rotation. After the door has been thus tightly closed, the key actuated lock D is pressed inwardly by the attendant, thus engaging the locking pin 41 of said lock with the keeper B to lock the same against rocking movement, and further projecting said pin into the path of swinging movement of the lug 47, thereby also locking the crank member K against rotation.

In closing the door by slamming the same shut, the operation is as follows: As the door is swung shut by the attendant, the cam lug 47 forcibly strikes against the keeper B, engaging the inclined cam face 33 thereof, thus, through the camming action between said lug and cam face, swinging the keeper on its pivot against the resistance of the spring C, as the lug rides along said cam face 33, as shown in Figure 9, until it clears the front wall of the keeper slot 31, whereupon the keeper swings back to its original position through the action of the spring C, in the manner of a swinging latch, over the lug 47 to lock the door closed. The parts having thus reached the latched position shown in Figure 4, the attendant depresses the key controlled lock D to project the pin 41 thereof through the keeper B and into the path of movement of the lug 47 of the crank member K to positively lock said keeper against rocking and the keeper engaging crank member against rotation.

In the event that it becomes necessary to open the door from the inside of the truck body, due to the attendant becoming trapped by the door accidentally swinging shut and latching in the manner hereinbefore described, the door may be readily opened by actuating the lever F. As the lever F is swung upwardly and away from the wall of the truck body, the plunger G is projected outwardly against the tail of the keeper B, thereby swinging the latter on its pivot and withdrawing it from operative latching engagement with the lug 47 of the keeper engaging crank member K, whereupon the door may be pushed fully open.

As will be understood this interior operating means is only for emergency use when the door

accidentally slams shut and becomes latched, as it cannot be operated so long as the keeper B is locked in fixed position by the key controlled lock D.

I have herein shown and described what I now consider the preferred manner of carrying out my invention, but the same is merely illustrative and I contemplate all changes and modifications that come within the scope of the claims appended hereto.

I claim:

1. In a fastener for a hinged door of a container, the combination with a keeper engaging crank member mounted on the door; of a keeper mounted on the container adjacent the door, said keeper having a guide slot provided with opposed walls, said crank member being engageable within the slot of the keeper and having camming engagement with the walls thereof to force the door either partly open or tightly closed, said keeper being spring resisted to permit yielding of said keeper when engaged by said crank member upon said door being slammed shut.

2. In a fastener for a hinged door of a container, the combination with a rotary crank member mounted on the door, said crank member having an eccentric cam lug thereon; of a spring actuated latch member mounted on the container in the path of movement of said cam lug during swinging movement of said door to closed position, said latch member having a slot having side walls within which said cam lug is engageable, said cam lug having camming engagement with the walls of said slot to force the door closed when said crank member is rotated in one direction and to force the door open when said crank member is rotated in a reverse direction.

3. In a fastener for a hinged door of a container, the combination with a rotary member having an eccentric cam lug thereon; of means for latching said door in closed position comprising a pivoted keeper adapted to swing into latching engagement with said eccentric cam lug to hold the door in closed position; and manually controlled means, actuated from within the container for swinging said keeper out of engagement with the cam lug to permit said door to be swung open, said cam lug forcibly camming said door shut or open by engagement with said keeper by rotation of said member in reverse directions.

4. In a fastener for a hinged door of a container, the combination with a keeper engaging crank member mounted on the door; of a yieldingly mounted slotted keeper with which said crank member is engageable to pry the door open or force the same tightly closed, when said crank member is rotated in reverse directions, said crank member having camming engagement with the keeper when said door is slammed shut to force said keeper to yield and permit engagement of said crank member within the slot of the keeper; and a key-controlled plunger lock engageable with said keeper to lock the same against rocking movement, and having a portion projecting into the path of movement of said crank member to lock the latter against rotation in door opening direction.

5. In a fastener for a hinged door of a container, the combination with a rotary operating member mounted on the door, said member having an eccentric keeper engaging cam thereon; of a keeper swingingly mounted on said container, said keeper having a slot provided with opposed

walls between which said cam is engageable; a cam face on said keeper with which said cam has engagement when the door is being slammed shut; and spring means yieldingly resisting swinging movement of said keeper.

6. In a fastener for a hinged door of a container, the combination with a rotary operating member mounted on the door, said rotary member having a cam lug eccentric to its axis of rotation; of a keeper on said container having an outwardly opening, inclined cam slot provided with side walls between which said cam lug is engageable; a cam face on said keeper at the entrance to said slot and in the path of movement of said cam lug when the door is being slammed shut; a pivot on which said keeper is swingingly supported; and a spring yieldingly opposing swinging movement of said cam lug.

7. In a fastener for a hinged door of a container, the combination with a keeper; of pivot means on which said keeper is rockingly supported, said keeper having head and tail portions at opposite sides of said pivot; a spring pressing on said tail portion to yieldingly hold said head portion outwardly away from the container, said head portion being slotted to provide spaced walls; a crank arm rotatably mounted on the door; and a crank pin on the outer end of said arm engageable between the walls of said slot of the keeper, said keeper being in the path of movement of said crank pin when the door is slammed shut to be engaged by said pin and swung to register the slot of the keeper with the crank pin.

8. In a fastener for a hinged door of a container, the combination with a housing fixed to the container adjacent said door; of a pivoted keeper within said housing, said keeper having a slotted head to provide a guideway having spaced side walls; spring means reacting between said housing and keeper for yieldingly pressing said head away from the container; an operating crank member rotatably mounted on the door, said crank member having a cam lug thereon engageable between the side walls of said guideway of the keeper; and cam means on said keeper in the path of movement of said cam lug and having camming engagement with the latter when the door is being slammed shut, for swinging said head portion of the keeper inwardly to an extent to register the guideway of the keeper with said cam lug and permit said spring to throw the keeper into latching engagement with said cam lug.

9. In a fastener for a hinged door of a container, the combination with a crank member rotatably mounted on the door, said crank member including an eccentric keeper engaging lug; of a keeper having a cam slot within which said lug is engageable; a housing fixed to the container adjacent said door; means pivotally supporting said keeper in the housing in the path of movement of said keeper engaging lug; spring means within the housing resisting pivotal movement of the keeper; and a key-controlled lock on said housing having a locking pin portion adapted to engage with said keeper to lock the same against rocking movement, said pin extending into the slot of the keeper to block rotary movement of said keeper engaging lug in door opening direction.

10. In a fastener for a hinged door mounted on a wall of a container, the combination with a rotary crank member mounted on the door and having an eccentric keeper engaging pin thereon; of a housing fixed to the outer side of the con-

tainer; a combined latch and keeper pivoted for swinging movement in said housing, said combined latch and keeper having a slotted head portion and tail portion, said head and tail being on opposite sides of the pivot of said keeper, said slot of the head receiving the pin of said crank member to hold the door closed; a spring interposed between the tail of said keeper and a wall of said housing to press said tail inwardly toward

5 said wall of the container to force said slotted head outwardly away from said wall, a push rod extending through the wall of the container and engaging the inner side of the tail of said keeper; and a handle lever pivoted on the inner side of said wall and having a pivotal connection with said rod.

WILLIAM M. DWYER.
